(57) **CLAIM**

The ornamental design for "aircraft interior divan," as shown and described.

DESCRIPTION

FIG. 1 is a front perspective view thereof,
FIG. 2 is a front elevational view thereof,
FIG. 3 is a rear elevational view thereof,
FIG. 4 is a top plan view thereof,
FIG. 5 is a bottom plan view thereof,
FIG. 6 is a left side elevational view thereof; and,
FIG. 7 is a right side elevational view thereof.
The broken lines in the FIGURES represent structures in the environment of the claimed design which do not form any part of the claimed design.
